United States Patent

Des. 240,887
Patented Aug. 10, 1976

240,887

CRUET

Robert H. C. M. Daenen, Aalst, Belgium, assignor to
Dart Industries Inc., Los Angeles, Calif.

Filed Apr. 28, 1975, Ser. No. 572,033

Term of patent 14 years

Int. Cl. D7—01

U.S. Cl. D7—59

FIG. 1

FIG. 2

FIG. 3

FIG. 1 is a top plan view of a cruet showing my new design;

FIG. 2 is a bottom plan view thereof;

FIG. 3 is a front elevational view thereof;

FIG. 4 is a side elevational view thereof;

FIG. 5 is a rear elevational view thereof; and

FIG. 6 is a cross-sectional view thereof taken along line 6—6 of FIG. 3.

I claim:

The ornamental design for a cruet, substantially as shown.
